UNITED STATES PATENT OFFICE.

FRANK C. NEWELL, OF WILKINSBURG, PENNSYLVANIA, ASSIGNOR TO WESTINGHOUSE ELECTRIC & MANUFACTURING COMPANY, A CORPORATION OF PENNSYLVANIA.

ELECTRIC SWITCH MECHANISM.

No. 846,840.

Specification of Letters Patent.

Patented March 5, 1907.

Application filed April 4, 1902. Serial No. 101,414.

To all whom it may concern:

Be it known that I, FRANK C. NEWELL, a citizen of the United States, residing at Wilkinsburg, in the county of Allegheny and State of Pennsylvania, have invented certain new and useful Improvements in Electric Switch Mechanism, of which the following is a specification.

My invention relates to electric switches and especially to means for making and breaking contacts in conductors carrying heavy currents. Its primary objects are to provide a switch which will be quick and positive in its action, and yet capable of great facility of manipulation, to avoid injury to the contacting parts, and hold the contacts together when the circuit is made without the loss of appreciable energy, and which will, when the contact is broken, act by means of a combination of magnetic fields to blow out the arc.

Further objects of my invention are to provide mechanism whereby a main circuit can be made and broken by means of a pilot switch which may be located at some distance from said circuit; and to use the temporary effect of very suddenly reducing resistance to quicken the action of an electromagnet and increase the rapidity of operation of the switch.

These objects and other advantages which will hereinafter appear, I attain by means of apparatus which I have diagrammatically illustrated in a preferred form in the accompanying drawing, wherein—

Figure 1 shows the apparatus applied to a switch as I prefer to construct it, and

Figure 2 is a diagrammatic illustration of the circuits, intended to make certain features and action of the improvement clear.

Referring in the first instance to Figure 2; I provide a source of current 3, in a main circuit with some form of translating device 4, such for example as a motor a lamp, or any other apparatus of like kind, the main circuit wire being marked 5, and being provided with a main circuit switch 6. The main circuit includes two relatively movable contact terminals 7 and 8, which are of soft iron, and form cores of a solenoid coil 9. This is in what I shall for convenience call a pilot circuit which includes also the connections 10 and high inductance coil 11, the pilot circuit

being always in connection with coil 11, and also provided between points *x* and *y* with a short-circuiting pilot switch 12, in conductor 18. It serves the purpose of short circuiting the high inductance coil 11 in the operation of the device, which will be hereinafter more particularly described. In practice coil 11 is wound around the terminals 7, 8, or 13, 14, in Figure 1, and in a direction opposed to the winding of coil 9, as there shown.

As the pilot switch 12 at no time has to carry any very large current, and as in the breaking of the same, as will hereinafter appear, there is an inductive action set up in the circuit which tends to prevent any arcing at the switch, the said pilot switch can be a very fine and delicate device, readily manipulated, and cheap to construct, it being only required that it shall be closed and opened positively, that is, without tremulation or shaking.

The movable terminals 7 and 8 of the main circuit automatic switch are constructed so as to move toward and away from each other, being either one fixed and the other movable, or both movable, as preferred. In the construction shown in Figure 1, I have indicated one of them as fixed, and the other relatively movable.

The operation of the mechanism shown in Figure 2, is as follows:

Assuming that the main circuit has a resistance many times that of the solenoid coil 9, and the higher inductance coil 11, a resistance much greater than both of these together, it is obvious that when the main contacts 7 and 8 are separated as shown in Figure 2, there will be no current passing through them, but that there will be a very slight current passing through the solenoid coil 9 as well as coil 11, these being both in the pilot circuit. This current is continuous but of so small capacity as not to draw the contacts 7 and 8 together against the influence of coils 11. If now the pilot switch 12 be closed, this will short circuit the coil 11 and cut out of the pilot circuit the heavy resistance, and thus produce a largely increased current in the solenoidal coil 9, which will cause the terminals 7 and 8 to close. At the same time the sudden increase of flow in the whole main circuit, including the coils 9, will produce sudden intense magnetization of the coils of

the solenoid 9 and pull the cores 7 and 8 together with great violence, making a firm and secure contact with great rapidity. The two main contacts 7 and 8 having thus been brought together, there is immediately set up through them the main current, which continues to flow so long as they are held together, which condition will be continued by the very small amount of current still continuing to flow in the solenoidal coil as well as by the residual magnetism in the cores. The closing of the magnetic terminals 7, 8, is thus caused both by the mere increase of current in coil 9 due to cutting out resistance 11 from the circuit, and also quickened by the reflex impulse due to releasing the retarding influence of coil 11 when the resistance to flow is altered suddenly,—it being understood that a disturbance in the normal flow causes a vibratory inductance in the magnetizing coils and certain reactionary effects in the magnet cores which will cause their attraction to increase suddenly instead of building up slowly as would be the case if current were merely introduced to the coils tending to pull them together.

Considering now Figure 1, it will be seen that in arranging the automatic apparatus here shown, I have formed the main switch terminals in the shape of horse shoe magnets 13 and 14 and between their poles 13^a, 13^b, and 14^a, and 14^b, are two contact blocks 15 and 16, preferably made of brass, and loosely carried thereon so as to make contact without the actuating magnets actually touching each other. The magnet 13 with its contact 15 being stationary, and the magnet 14 with its contact block 16 being relatively movable, and preferably mounted so as to give slightly and make a close contact, the movement of the magnet coil being longitudinal through the magnetic casing 17 which incloses the apparatus. The high resistance coil 11 in this Figure 1 is disposed about the horse shoe magnet so that the winding will tend when not short circuited to produce a like polarity of opposing poles of the magnet so as to produce a repellent action between the poles opposite to each other. The winding of these coils 11 is thus disposed so that the horse shoe magnets when the current is normally flowing through the high resistance coils, the pole 14^a, for example, will be a north pole, and the pole 14^b a south pole, while the pole 13^a will be normally a south pole, and the pole 13^b normally a north pole. Thus the polarity of 13^a and 14^a is alike, as also 13^b and 14^b, and there will be strong repellent action tending to hold the contacts apart. During this time the repellent forces of the poles of the magnets will be very much in excess of the polarization effect produced by the solenoid coil 9, since there is much more wire wound around the horse shoe magnet poles than there is in the solenoidal coil, and

since the several coils are in series the current intensity or flow is the same in both. The casing 17 reduces the reluctance of the device by completing the magnetic current when the two terminals are in contact.

The operation of the device shown in Figure 1 is similar to that shown in Figure 2, but also embodies in addition the results attained by the peculiar arrangement of the horse shoe magnets, and the polarity thereof produced by the winding of the high resistance coils. The closing of the terminals is effected as before described in the apparatus of Figure 2.

To separate the main terminals 7 and 8 the pilot switch 12 is opened so as to break the short circuit around the high resistance coils, which brings the said coils into operation, again, and produces the horse shoe magnet action already described, which immediately causes intense magnetization of the horse shoe magnets, which, as already explained, have their opposite poles of like polarity, and this being of much greater force than the magnetic effect produced through the solenoidal coil alone, entirely overcomes the action of the solenoidal coil, and acts upon the terminals 7 and 8 to drive them apart with greater violence, breaking the circuit quickly, and at the same time creating a magnetic flux which blows out the arc, so far as any arc may be produced, by the magnetic flow across the arc path. Thus the magnetization creates a magnetic field flowing in substantially five different paths which all tend to intercept the arc which may be produced between the terminals 15 and 16, that is a magnetic flux from 14^a to 14^b, one from 13^a to 13^b, one from 13^a to 14^b, one from 14^a to 13^b, and one substantially straight across. This produces magnetic lines of force in a direction transverse to the direction of the arc, which tend to blow out any arc.

Having thus described my invention and illustrated its use, what I claim as new, and desire to secure by Letters Patent, is the following:

1. The combination with a pair of separable contact terminals having magnetizable parts, of an energizing winding for holding said contact terminals in engagement, a second winding of stronger force adapted to separate them, and a shunt and switch for shunting out the more powerful winding to allow the terminals to come together.

2. The combination with a pair of separable contact terminals having magnetizable parts, of an energizing winding for holding said contact terminals in engagement, a second winding adapted to separate them, and a shunt and switch for shunting out the second winding to allow the terminals to come together.

3. The combination with a pair of separable contact terminals having magnetizable

parts, of a winding around said terminals tending to magnetize them to attract them together, a high resistance winding in circuit with said first winding and tending to keep the magnetism below the strength at which the terminals will be brought together, and a shunt and pilot switch for shunting out the high resistance winding.

4. The combination with a pair of separable contact terminals having magnetizable parts, of an energizing winding for holding said contact terminals in engagement, a second winding adapted when fully energized to separate the contact terminals, and means for deenergizing said second winding to a strength less than that of the first winding to permit the first winding to actuate the terminals.

5. The combination with a pair of separable contact terminals having magnetizable parts, of an energizing winding for holding said contact terminals in engagement, a second stronger winding adapted when energized to separate said contact terminals, and means for deenergizing said second stronger winding to a strength less than that of the first winding to permit the first winding to actuate the terminals.

6. The combination of a main circuit, main circuit terminals comprising parts of the core of a solenoid, the solenoid around said terminals being attached to the main circuit and being in series with a pilot circuit, a higher resistance coil in said pilot circuit, a shunt for said high resistance coil and a switch for opening and closing the said shunt circuit.

7. The combination with two relatively movable terminals, of a main circuit with a solenoid surrounding said terminals wound to secure unlike polarity at the terminals, a high resistance coil connecting to said solenoid and to the main circuit and wound to secure like polarity of the terminals, and a shunt with a switch therein whereby the cur-

rent through the high resistance coil may be reduced in order to increase the current in the solenoid to draw said terminals together.

8. The combination of two relatively movable terminals comprising contact blocks and horse shoe magnets surrounding the same, a solenoid surrounding both of said magnets as a whole and wound to secure unlike polarity of the terminals, high resistance coils wound upon each leg of said horse shoe magnet in such a way as to secure like polarity of the terminals, and a shunt and switch for shunting out the high resistance coils.

9. In combination, a main circuit, a pair of separable contact terminals therefor having magnetizable parts, a coil therefor, a supplementary resistance coil normally in series with the first coil and in a shunt to the main circuit, and a pilot switch and shunt to shunt out the supplemental coil whereby to increase the current in the first coil and close the terminals.

10. The combination with a pair of separable contact terminals having magnetizable parts, of a winding to cause them to be attracted toward each other to close the circuit, a stronger winding adapted to hold the terminals apart, and means to shunt out this latter coil.

11. The combination with a pair of separable contact terminals having magnetizable parts, of electric coils on the terminals adapted to magnetize them for attraction and other supplemental electric coils thereon adapted to magnetize them for repulsion, whereby the terminals are closed or opened by decreasing or increasing the current in said supplemental coils.

In testimony whereof I have hereunto set my hand in the presence of two subscribing witnesses.
